(57) **CLAIM**

We claim the ornamental design for the sofa bed for cruise ship, as shown and described.

DESCRIPTION

FIG. 1 is a first perspective view of a first embodiment of the sofa bed for cruise ship of the present invention.

FIG. 2 is a front view of the invention shown in FIG. 1.

FIG. 3 is a rear view of the invention shown in FIG. 1.

FIG. 4 is a side view of the invention shown in FIG. 1.

FIG. 5 is a second side view of the invention shown in FIG. 1.

FIG. 6 is a top view of the invention shown in FIG. 1; and, FIG. 7 is a bottom view of the invention shown in FIG. 1. The ornamental design which is claimed is shown in the solid lines in the drawings.

1 Claim, 7 Drawing Sheets
